UNITED STATES PATENT OFFICE.

JOHN W. BEACHAM, OF MONTGOMERY, AND BENJAMIN F. POWERS, OF BIRMINGHAM,
ALABAMA.

AUTOMATIC TRAIN-PIPE COUPLING.

1,167,789.

Specification of Letters Patent. Patented Jan. 11, 1916.

Application filed November 19, 1913. Serial No. 801,913.

To all whom it may concern:

Be it known that we, JOHN W. BEACHAM and BENJAMIN F. POWERS, citizens of the United States of America, residing, respectively, at Montgomery, in the county of Montgomery and State of Alabama, and at Birmingham, in the county of Jefferson and State of Alabama, have invented certain new and useful Improvements in Automatic Train-Pipe Couplings, of which the following is a specification.

Our invention relates to automatic coupling mechanism for the air, steam and signal pipes of trains, and our object is to provide a simple, cheap and thoroughly practical means which will effectively couple the train pipes and which will avoid the necessity of changing the present standard arrangement of piping and other mechanism on the cars.

A further object of our invention is to enable cars equipped with our automatic coupling attachment to be readily coupled with cars not similarly equipped so that no inconvenience will be experienced in the use of our coupler attachments in coupling trains of cars, some of which have no automatic train pipe coupling mechanism. To this end our automatic coupler attachments are coupled up to the present standard train hose and can be readily uncoupled from the hose, thereby cutting out the automatic attachment and permitting the hose of adjoining cars to be coupled by hand.

A further object of our invention is to provide a novel and effective means for mounting the automatic attachment on the draft timbers or car bodies so as to hold them yieldingly in correct coupling position and yet leave them free to follow the maximum angular variations both vertically and horizontally between coupled cars. The point to which the couplers are attached makes them independent of the car coupler.

A further object is to provide the coupler heads with a novel form of interlocking guide members which will not only guide the coupler heads into coupling position under maximum relative variations in their positions, but, after guiding the heads together, will interlock them rigidly on both sides to prevent any relative movement between them while coupled.

A further object is to yieldingly mount the heads so that they are held together by

very heavy spring pressure and to provide means to protect the gaskets, which are used to insure tight joints, from being injured by this heavy pressure.

A further object is to so design the coupler heads for freight and passenger cars that the air brake connections of a freight car can be automatically coupled to the air brake connections of a passenger train and the interposition of a freight car will have no other effect than to interrupt the steam heating and signal connections to cars in the rear of it.

Our invention further comprises the details of construction and arrangement of parts which we regard as the preferred embodiment of our invention and which are hereinafter more particularly described and claimed, reference being had to the accompanying drawings, in which:

Figure 1 is a bottom view of freight cars equipped with our automatic train pipe couplers. Fig. 2 is a side elevation of Fig. 1, showing the present style of air hose in full lines connected to our automatic couplers, and in dotted lines, the hose are connected together manually, thereby cutting out the automatic couplers. Fig. 3 is an enlarged detail view showing the bracket supports in perspective for the automatic coupler, the head of which is shown in vertical cross-section. Fig. 4 is an enlarged front view of a coupler head for use on passenger coaches. Fig. 5 is a perspective view showing two passenger car coupling heads as they approach to couple. Fig. 6 is a detail view of the gasket and its locking pin, and Fig. 7 is a side elevation showing the coupler heads for passenger and freight cars coupled.

Similar reference numerals refer to similar parts throughout the drawings.

Our object being to produce a train pipe coupling equipment adapted for the purposes described which is rugged in its nature, requires a minimum of machine work and can be applied to cars without requiring any re-arrangement of their present standard equipment, we have shown as a preferred embodiment of our invention an automatic coupler head 1 for freight cars and a coupler head 2 for passenger cars, which heads are preferably cast integral with a stem 3 which is provided at an intermediate point with a shoulder or stop 4

95

10

10

11

serving as the forward seat for a heavy coiled compression spring 5. This spring surrounds the stem and at its rear end seats against a lug 6 through which the stem 3 passes freely. This lug seats against the rear bracket which comprises a vertical U-shaped metal frame 7 and an intermediate transverse brace bar 8 having its angled ends bolted to the inner vertical sides of the frame 7. The lug 6 fits slidingly against this bar and the bottom of the frame 7 and is adapted to swing horizontally with the rear end of stem 3 which is held normally in the center of the bracket by means of a pair of coil springs 9, one of which is disposed on each side of the stem and has its outer end firmly held in a seat 9^a at a bottom corner of frame 7. The upper ends of the frame 7 pass on the outside of the draft timbers and have top flanges which are in-turned and perforated to receive bolts for fastening them to the draft timbers. This frame is further braced by rearwardly disposed struts 11 which are bolted to the underside of the frame 7 and to the draft timbers. The stem 3 is perforated at its rear end and receives a stop pin 12 which holds a washer 12^a that is adapted to engage the rear bracket and stop the forward travel of the stem 3, under the influence of spring 5, when the cars uncouple. At its forward end the stem 3 rests on a front U-shaped bracket 13 having its upper ends 14 passing up between the draft timbers and provided with outturned, perforated flanges by which it is bolted firmly in place. Neither bracket in any way interferes with the draw-bar of the car coupler, and if desired they can be secured in any suitable manner to the body 40 of the car. The stem 3 is confined by the forward bracket to adjustments vertically, being guided by means of an inverted U-shaped frame 15 having slightly greater width than the stem itself and which is bolted to the base member of the bracket 13. At its upper end the frame 15 has a depending stud 16 connected thereto which serves to hold in operating position in said frame the coil spring 17 which presses the stem 3 50 downwardly against the bracket. The frame 15 has sufficient clearance to permit the stem to pivot on it as its rear end shifts sidewise in the rear bracket but it co-acts with the springs 9 to normally hold the stem 55 and coupler head in alinement with the longitudinal center line of the car. Also the stem has enough clearance in the rear lug 6 and in the rear bracket to permit its forward end to rise and fall vertically in the frame 15 of the front bracket. The spring 5 is designed to have a compression so as to overcome all lost-motion in the coupling connections of two cars and is designed to maintain a high pressure, say at least 200 65 pounds, on the stem and coupling head

when the cars are stretched out under pull or when they are uncoupled. We prefer that the springs 5 should be under heavy compression even when the car is not coupled so that the high compression desired 70 can be obtained in the relatively small longitudinal movement of the stem required.

Referring now to the design of the coupler head, we have shown two forms which are illustrated in side elevation in Fig. 7, 75 the head 1 being designed for use with freight cars which are equipped with only a single train line pipe 18 for the air brake pressure. The coupler head 2 is adapted to couple two other pipes, namely, the air signal pipe line and the steam heating pipe line. Both heads are similar at their upper portions containing the air brake connections but the heads 2 are deeper to accommodate the two additional connections required for the signal and steam heating pipes. The heads are preferably cast integral with the stems and when cast are formed with an air brake pressure passage 19 which leads from the side of the head inwardly and then at an angle out through the front end of the head. The coupler heads for passenger cars have a similarly arranged but smaller passage 20 for the air signal and below that a third passage 21 for the steam heat. The upper passages 19 and 20 open out through one side of the coupler head while the lower passage 21 for the steam opens out through the opposite side of the head. These side openings have 10 threads tapped therein and elbows 22 are screwed therein, and to each elbow is connected a flexible hose having at its lower end one member of the ordinary type of train hose coupling 23. The hose 24 connects with the air brake passage 19, the hose 25 with the signal passage 20, and the hose 26 with the steam passage 21. The air brake train line 18 is provided with the usual flexible hose 27 having couplings 28 1: which are adapted to be brought together by hand and coupled as is the present practice. The hose 27 are also adapted to be coupled to the hose 24 on the automatic coupler when the air brake system is to be 1 automatically coupled.

Passenger coaches may be provided with the customary arrangement of steam and signal pipes (not shown) and these will have hose 28 and 29 respectively, connected 1 thereto and adapted either for manual connection to similar hose on another car, when the automatic mechanism is cut out, or for connection respectively to the hose 25 and 26, when it is desired to use the automatic 1 coupler. At their forward ends the several passages 19, 20 and 21 are enlarged to receive gaskets 30. These gaskets when used in connection with the steam pipe lines are preferably formed of a composition of as- 1

bestos and rubber so that they will not be injured by the heat. Otherwise they can be made of rubber or other suitable material. These gaskets, as shown in Fig. 6, are provided about their centers with a circumferential groove 31 which registers with a vertical bolt hole through the head so that a bolt 32 can be passed down through the head and caused to engage in the groove 31 of each of the several gaskets and hold them against disengagement. The gaskets are designed to project beyond the forward face of the coupler head and are protected against being crushed by offset shoulders 33 at the top and bottom of the front face of the coupler head. These shoulders are offset less than the gaskets normally project so that the gaskets are subjected to sufficient compression when the heads are coupled to insure a tight joint and yet avoid being crushed under the heavy compression strain exerted on the heads by the action of springs 5 on the coupler stems 3.

Each coupling head, whether for passenger or freight cars, is provided with members for guiding the coupling heads together and locking them tightly together when coupled. These means comprise a shank 34 attached to or molded on one side of the head. This shank is preferably made square and at its outer end is tapered outwardly to a point, being joined to the head at a point substantially opposite the passage 19. On the other side of the head is molded or otherwise attached a funnel shaped guide box 35. The funnel end of the box stands flush with the front face of the coupler head and converges on a gradual taper from all sides to a square extension lock box 36 having a cross-sectional opening made just large enough to receive the square body portion of the shank member 34 so that when the shank is forced home into the guide box it will make such a snug fit in the extension 45 36 that it will hold the couplers rigid. The shank 34 is given extra length and the guide box 35 is correspondingly elongated to increase the total bearing between these parts and to insure them holding the couplers rigid. Inasmuch as each coupler is provided with a shank 34 and guide box 35, they are interlocked on each side. In order to increase the displacement which the guide boxes will provide for and still act to guide 55 the heads into coupled position, we groove or cut away the inside front face of the coupler at 37. The shanks and guide boxes have the same relative position on the upper end of the coupler for both passenger and freight equipment, as will be seen by reference to Fig. 7, so that a freight car can have its air brake line automatically coupled with that of a passenger car. The signal and steam heating train lines will obviously be 60 interrupted at the freight coupler. The 65

freight car coupler may be equipped with the ordinary type of rubber gasket as it will not be subjected to heat.

The automatic couplers are preferably disposed about six inches below the draw head and from seventeen to nineteen inches from the top of the rails, this placing them out of position to interfere with or be injured by the car coupler and in position for being conveniently coupled into or cut out 75 of the train pipe system.

In practice we have found it desirable to give the stem 3 a lateral clearance of approximately two inches and a vertical clearance of approximately six inches within the 80 frame 15. The manner of locking the gaskets in position prevents them jarring or working loose and they will not wear rapidly due to the fact that the guide means lock them against relative movement while 85 coupled and in uncoupling they separate without a twisting movement. The bracket construction shown we regard as preferable in that it most effectively holds the heads in proper alignment for coupling while permitting them the maximum angular play required. 90

We desire it understood, in the event the use of our equipment should become so general that it would be unnecessary to provide 95 for coupling to cars without automatic equipment, that the train pipes can be direct connected to the passages in the coupler head in any suitable manner.

In effecting a coupling the compression 100 springs 5 will hold the pipe coupling heads in advance of the car couplers so that the pipe coupling heads engage and their springs are put under considerable additional compression before the car coupling 105 is made. This extra compression on the springs causes them to compensate for the push and pull variation in distance between the cars. The springs and parts are designed to provide for a sufficient compression 110 to hold the pipe coupling heads in positive coupled engagement throughout the maximum relative movements between coupled cars.

Having thus described our invention, what 115 we claim as new and desire to secure by Letters Patent, is:—

1. A train pipe coupling comprising a member having a conduit therein and means to guide and interlock therewith another 120 coupling member, said means comprising on one side of the member a projecting guide arm tapered outwardly from its inside to its outside side edges and having a straight outer side edge and on the other side a funnel 125 shaped guide box converging into a rear lock box having a greater length than the guide box and shaped and positioned to receive and bear against the long outer side of the guide arm of another coupler, a suffi- 130

cient portion of the arm fitting into said lock box to rigidly interlock said parts.

2. In a train pipe coupling, in combination, a coupler member having a conduit, a rearwardly extending stem for said member, front and rear brackets adapted to be fastened to a car, the front bracket having a narrow vertical guide frame in which the stem fits loosely enough to pivot about its sides and to move vertically, a spring adapted to hold the stem against the bottom of the guide frame, the rear bracket having a horizontal guide frame in which the stem fits loosely and is free to swing laterally, spring means to hold the stem centrally of said rear bracket, spring means to urge the stem longitudinally outwardly through said brackets, and stop means to limit the outward travel of said stem.
3. In combination, a train pipe coupler and supporting mechanism therefor comprising a front bracket having its vertical legs adapted to be received between and attached to the draft sills, a vertical coupler guide mounted in said bracket, a rear bracket having its vertical legs adapted to embrace the outer sides of the draft sills and to be attached to said sills, a horizontal coupler guide mounted in said rear bracket, rear brace means for said rear bracket, spring means in said brackets to center the coupler, and spring means to urge the coupler forwardly in its supports.
4. In a train pipe coupler, a coupler head having one or more conduits and means to connect same with the train pipe connections, of a shank for supporting said conduits, a pair of brackets for supporting the shank, the forward bracket having fast therein a narrow vertical guide frame in which the shank is guided for adjustment in a vertical plane and about which the shank is angularly adjustable, a spring to oppose said vertical adjustment, a rear bracket having a narrow horizontal guide frame in which the shank is confined to adjustments in a horizontal plane, springs which hold said shank normally in the center of said latter frame, spring means to urge the shank forward, and a removable stop to engage 50 a bracket and arrest the forward travel of the shank, substantially as described.
5. In a train pipe coupler comprising a coupling head and shank, and means for mounting the shank in adjustable position 55 under a car comprising a front U-shaped bracket adapted to be connected to the car body, a narrow inverted U-shaped frame connected to the bottom of the bracket and adapted to receive in it for vertical adjustment said shank, a spring mounted in said frame and acting to hold the shank against the bottom of the bracket, a rear bracket also connected to the body of the car and comprising a transverse bar which forms 60 with the bottom of the bracket a horizontal guide in which the shank is movable horizontally and longitudinally but not vertically, spring holders set in each end of said horizontal guide, springs connected to said 65 holders and adapted to slidingly engage the shank on each side to hold it centrally of the rear bracket while permitting it to shift horizontally therein, a washer through which the shank passes loosely and which 70 bears against the front of the rear bracket, a stop disposed on the shank between said brackets, a coiled spring surrounding the shank and seated against said washer and stop, and a stop on the shank to the rear 75 of said rear bracket, said forward guide of said rear bracket, said forward guide frame permitting the shank to move angularly therein as its rear end swings horizontally in the rear bracket, substantially 80 as described.
